UNITED STATES PATENT OFFICE.

HARRY JOHNSON AND CARL E. GUSTAFSON, OF CHICAGO, ILLINOIS.

PORTABLE RECEPTACLE.

Application filed October 12, 1927. Serial No. 225,629.

This invention relates generally to a portable receptacle and more specifically to a receptacle which is particularly adapted for use in carrying large amounts of material.

5 In certain occupations, as for example that of janitor or the like, it is frequently necessary to transport large masses of material, such as waste paper, garbage and rubbish, from certain parts of the building where the 10 material accumulates to a central station from which it is removed from building.

It is an object of the invention to provide a new and improved portable receptacle especially adapted for the convenient transportation of material of this character, which receptacle is also arranged to facilitate the removal of such material therefrom.

Other objects and advantages will become apparent from the following description and 20 in the accompanying drawings, in which:

Figure 1 is a side elevation of a preferred form of the invention showing the manner in which the receptacle is carried.

Fig. 2 is a somewhat similar view showing 25 the manner in which the receptacle facilitates the removal of the contents therefrom.

Figs. 3 and 4 are detailed sectional views of parts of the invention.

In attaining the objects of the invention a 30 relatively large receptacle 5 is provided, which, in general, may have any preferred shape. In the present embodiment the receptacle is formed of galvanized sheet metal of substantially tubular shape and is provided 35 with a bottom 6 secured to the sides in any suitable manner as by means of the rivets 7. If desired a reinforcing strip 8 may be secured about the periphery of the bottom. In order to facilitate the carrying of the receptacle from place to place the receptacle is provided 40 with a concave portion 9 extending longitudinally of the receptacle and of such dimensions that the concaved side will rest snugly upon the body of a person carrying the receptacle.

Since the receptacle may be quite cumbersome means is provided which facilitates the raising of the receptacle into its proper position upon the back of a person and for carrying 45 and retaining the receptacle in that position which, in the present instance, comprises a strap 10 suitably secured to the receptacle. Preferably the strap 10 is in the form of a relatively loose loop which may be adjusted 50 for the convenience of the operator in any well

known manner, as by means of the adjustable buckle 11. The means by which the strap is attached to the receptacle preferably comprises means which permits the strap to slide or move relative thereto for a purpose to be 60 hereinafter set forth. To this end the strap 10 is attached near the upper portion and at one side of the concave portion of the receptacle by means of a relatively wide substantially U shaped member 12, which is secured 65 permanently through both legs of the U to the receptacle in any suitable manner, as by the rivets 13. In this manner an eye is provided through which the strap passes to be secured to the receptacle. If desired, a reinforcing strip 14 may be secured across the inner surface of the receptacle at this point. The strap 10 is also secured near the bottom and on the opposite side of the concave portion from the U shaped member 12 by means 70 of a similar U shaped member 15 secured thereto by means of the rivets 16. Preferably a handle 18 is provided for steadyng the receptacle on a person's back and to this end the U shaped member 15 is extended at one 75 end outwardly beyond the edge of the concave portion of the receptacle and is then bent inwardly and secured to the side of the receptacle as by means of the rivet 17. In use the operator may fill the receptacle with refuse 80 material and then by grasping the strap 10 may easily swing the receptacle into position upon his back in which position the receptacle may be most easily carried from place to place. When the operator has reached a place 85 where it is desired to remove or "dump" the material from the receptacle he may grasp the handle 18 in one hand and the strap 10 in the other and permit the receptacle to swing 90 from its carrying position. As the receptacle swings downwardly, the manner in which the operator grasps the handle and the strap, causes the receptacle to swing into the position shown in Fig. 2, wherein the material 95 may readily be ejected therefrom. During the swinging movement of the receptacle from the carrying position to the dumping position the strap 10 is permitted to slide freely 100 through the eyes formed by the U shaped members 12 and 15 so that it is unnecessary for the operator to change the position of his hand upon the strap. Obviously the positions of the upper and lower U shaped members 12 and 15 may be changed from one side of the 105 concave portion of the receptacle to the other 110

to provide that the strap may pass over the right or left shoulder of the operator as desired.

It will be apparent from the foregoing that a portable receptacle has been provided which is simple and inexpensive in construction and which is adapted to facilitate the movement of material from place to place.

While the invention is susceptible of various modifications and alternative constructions, we have shown in the drawings and have herein described in detail the preferred embodiment, but it is to be understood that we do not thereby intend to limit the invention to the specific form disclosed, but intend to cover all modifications and alternative constructions falling within the spirit and scope of the invention as expressed in the appended claims.

20 We claim as our invention:

1. A portable receptacle comprising, in combination, a bottom, a side wall secured thereto, said side wall having a longitudinal portion thereof concave to fit about the back of a person, and means for supporting said receptacle upon the back of said person comprising a **U** shaped member secured to the receptacle near the top and at one side of the concave portion thereof, a second **U** shaped member secured to the receptacle near the bottom and at the opposite side of the concave portion from the first mentioned **U** shaped member, and a carrying strap passing through both of said **U** shaped members, said lower one of said **U** shaped members being extended in the form of a loop to provide a handle for said receptacle.

2. In a portable receptacle having a longi-

tudinal portion thereof concaved to receive the body of an operator, means secured to 40 said receptacle for supporting the receptacle upon the back of an operator while the receptacle is being carried from place to place and for maintaining said receptacle in a tilted position when the contents thereof are 45 being removed, said means comprising a carrying strap mounted on the receptacle at one point near the upper portion and adjacent one side of the concave portion thereof and being further secured to said receptacle at another point near the bottom and adjacent the other side of said concave portion, and a handle mounted on the side and near the bottom of the receptacle and adjacent to the concave portion.

3. In a portable receptacle of the character described, means secured to said receptacle for supporting the receptacle upon the back of an operator while the receptacle is being carried from place to place and for maintaining said receptacle in a tilted position when the receptacle is being emptied of its contents, said means comprising a supporting strap slidably mounted on the receptacle at one point near the upper portion and adjacent one side of the concave portion thereof, and being further slidably attached to said receptacle at another point near the bottom and adjacent the other side of said concave portion, and a handle secured on the side of the receptacle and adjacent to the lower point of attachment of the strap.

In testimony whereof we have hereunto affixed our signatures.

HARRY JOHNSON.
CARL E. GUSTAFSON.
